UNITED STATES PATENT OFFICE

126,050

DESIGN FOR AN ELECTRIC CLOCK

Norman Lipsky, New York, N. Y., assignor to
Joseph Gottlieb, Jersey City, N. J.

Application December 24, 1940, Serial No. 97,605

Term of patent 7 years

To all whom it may concern:

Be it known that I, Norman Lipsky, a citizen of the United States, residing at New York city, county of New York, and State of New York, have invented a new, original, and ornamental Design for an Electric Clock, of which the following is a specification, reference being had to the accompanying drawing, forming part thereof.

Fig. 1 is a top plan view of an electric clock showing my new design; and

Fig. 2 is a front elevational view of the same.
I claim:

The ornamental design for an electric clock, as shown.

NORMAN LIPSKY.
